Primary Examiner — Susan Bennett Hattan*Assistant Examiner* — S. Bryan Reinholdt, Jr.(74) *Attorney, Agent, or Firm* — McHale & Slavin, P.A.(57) **CLAIM**

The ornamental design for a cork-lined container, as shown and described.

DESCRIPTION

FIG. 1 is a front, left side isometric view of a cork-lined container.

FIG. 2 is a top isometric view of the cork-lined container of FIG. 1;

FIG. 3 is a front view of the cork-lined container of FIG. 1; and,

FIG. 4 is a right side view of the cork-lined container of FIG. 1, with the left side being a mirror image thereof.

The broken lines depict portions of the cork-lined container that form no part of the claimed design. The portions of the container not illustrated, including the top, rear and bottom of the container, form no part of the claimed design.

1 Claim, 4 Drawing Sheets(56)
